SHOE

Arthur J. Brauer and Frederick P. Wagner,
St. Louis, Mo.

Application May 14, 1934, Serial No. 725,465

4 Claims. (Cl. 36—58.5)

This invention relates generally to shoes, and particularly to so-called non-slips as used in the heel portions of shoes such as pumps and the process of making and applying the same.

It has heretofore been the practice, particularly in women's shoes of the pump type, to provide a device in the region of the heel for engagement with the side of the foot so as to reduce the tendency for the shoe to slip off the foot accidentally. Such devices as heretofore used have most generally been in the form of a piece of leather such as calf skin stitched to the upper in the region of the heel with the flesh side thereof exposed on the inside of the shoe. The use of this type of non-slip has been accompanied by the disadvantage that the offset relation of the surfaces, brought about by the presence of two distinct layers, has resulted in discomfort to the foot and sometimes in excessive wear upon the stocking. Moreover, because of the fact that such non-slips are ordinarily stitched to the inside of the lining, it often happens after some wear, that the securing stitches break and the non-slip becomes loose in the shoe, thus providing an additional source of annoyance.

Another form of non-slip which has heretofore gone into some use is a non-slip made of rubber, particularly sponge rubber, which is mounted on the inside of the shoe in the region of the heel and arranged to contact with the side of the foot or stocking, so as to reduce the tendency to slip. Such rubber devices, however, exert too much of a gripping force upon the foot or stocking and consequently their use has been accompanied by the disadvantages that excessive perspiration of the foot is caused in the region of contact, and furthermore that the stockings are pulled out of shape or displaced with reference to the foot during walking.

It is among the objects of the present invention to provide a non-slip device for shoes wherein the disadvantages referred to above are substantially reduced.

Another object of this invention is to provide a non-slip device for shoes and a process of applying the same, whereby the manufacturing operations may be accomplished with a minimum of effort and whereby a highly practical and efficient non-slip is provided.

Other objects will become apparent to those skilled in the art when the following description is read in connection with the accompanying drawing in which:

Figure 1 is a fragmentary view in side elevation of a shoe provided with a non-slip device constructed in accordance with the present invention and showing the heel portion of the upper in section.

Figure 2 is a plan view of a quarter lining of the shoe shown in Figure 1 and arranged to re-

ceive the non-slip constructed in accordance with the present invention.

Figure 3 is a plan view showing a piece of non-slip material cut for interlocking relation with openings formed in the quarter lining shown in Figure 2.

Figure 4 is a perspective view of a cushion such as a pad of sponge rubber employed in connection with the non-slip of the present invention.

Figure 5 is a sectional view taken along line 5—5 of Figure 1 and showing the quarter lining, non-slip material and cushion in assembled relation together with the other parts of the shoe upper.

Figure 6 is a plan view showing the quarter lining of Figure 2 and the non-slip of Figure 3 in assembled relation.

Figure 7 is a plan view of a quarter lining having a non-slip constructed in accordance with another embodiment of the present invention.

Figure 8 is a sectional view corresponding to Figure 5 but showing a non-slip corresponding to the embodiment of Figure 7.

Figure 9 is a plan view of a quarter lining arranged to receive a non-slip constructed in accordance with another embodiment of the present invention.

Figure 10 is a sectional view corresponding to Figure 5 but showing a non-slip according to the embodiment of Figure 9.

In accordance with the present invention, generally stated, a piece of non-slip material which may be leather arranged so as to provide a friction surface on the inside of a shoe may be passed through an opening in the quarter lining of a shoe so that the ends of a piece of non-slip material are between the folds of upper material in the finished shoe, while a central portion thereof is exposed so as to reduce the tendency of the shoe to slip on the foot. Such non-slip material may, as is the usual practice, be a piece of leather such as calf skin so arranged that the flesh side thereof is exposed on the interior of the shoe.

In accordance with one embodiment of the present invention, a cushion such as a pad of sponge rubber may be inserted beneath that portion of non-slip material which is exposed on the interior of the shoe to thus provide an additional force tending to extend the non-slip material beyond the plane of the lining and thus accentuate the anti-slipping tendencies. In accordance with another embodiment, however, the lining itself may be caused to provide the non-slip material and this may be accomplished by suitably roughening a portion of the lining or perforating the same. Beneath the roughened or perforated section of the lining may be applied a sponge rubber cushion, as mentioned above, so as to form a slight protuberance at that portion of the lining.

Referring now particularly to Figures 1 to 5 inclusive for an illustrative embodiment of the present invention, the shoe upper shown in Figure 1 may comprise a lining including a quarter lining 1 and an outside quarter section 2. In accordance with the usual practice, a counter 3 is inserted between the lining and the outside upper. In the region of the heel and provided so as to contact with the side of the foot is a non-slip 4 suitably secured as in the manner to be later described.

The non-slip 4 may, in accordance with one embodiment of the present invention, be formed by providing a pair of spaced openings 5 in the quarter lining 1 so as to provide a strip of intervening substance 6 between the openings. With this arrangement, a piece of non-slip material may be passed through one of the openings 5, over the intervening substance 6 and back through 20 the other opening 5 so that the ends of the non-slip material are concealed between the lining and the outside upper 2, while the intermediate portion (that is to say the portion which overlies the intervening substance 6) is exposed on the 25 interior of the shoe.

The non-slip material which, as mentioned above, may be a piece of leather or other suitable friction material, may be conveniently formed so as to interlock with the spaced openings 5. When 30 arcuate openings 5, such as those shown in Figure 2, are provided, a convenient shape for the non-slip material is that shown in Figure 3. The non-slip may be formed from a disk 7 of calf skin having a central portion 8 of substantially the same width as the width of openings 5, while at either side of the central portion 8 are wider portions 9 providing shoulders adapted to 35 interlock with openings 5 as shown in the dotted lines in Figure 6. As will be observed from Figure 6, the distance between the shoulders formed by the wider portions 9 correspond substantially to the width of the intervening substance 6 so that although no other securing means be present, the non-slip would readily hold itself in position because of the interlocking engagement with the openings 5. In order to provide a smoother 40 joint and neater construction the edges of the non-slip may be skived, as shown at 10.

In order to cause the non-slip 7 to slightly 50 protrude beyond the adjacent quarter lining 1, a cushion 11 which may be of sponge rubber or other suitable material may be interposed between the non-slip 7 and the intervening substance 6 of the quarter lining. It will be understood, of course, that some of the advantages of the present invention may be obtained without the use 55 of such a cushion 11.

A convenient procedure is to attach the sponge rubber cushion 11 to the grain side of non-slip 7 back of the central portion 8 thereof which is to be exposed on the inside of the shoe and then distort the wider portions 9 of the non-slip so as to pass the ends thereof through the respective openings 5 in the quarter lining. The device may 60 then be secured in position either by adhesive or by running a line of stitching 12 around the outside of openings 5, as shown.

In order to accentuate the non-slipping action, a series of perforations such as 13, may be provided in non-slip 7. The perforations are particularly beneficial when the non-slip is backed by a cushion such as 11.

Referring now to Figures 7 and 8, another embodiment of the present invention is shown,

wherein the cushion 11 is employed. In this case, however, the lining itself forms the cover for the sponge rubber cushion. In order to render that portion of the lining which is over the cushion 11 of anti-slipping character, it may be suitably 5 roughened or may be provided with a series of perforations 14 in the general region 15 which is to cover the sponge rubber cushion 11 and protrude beyond the adjacent lining.

In accordance with another embodiment, as illustrated in Figures 9 and 10, an opening 16 may be formed in the quarter lining 1 and a piece of non-slip material 17, which may be in the form of a circular disk centrally backed by sponge rubber cushion 11, may be applied so as to bulge 15 through opening 16 and be thereby exposed on the interior of the shoe.

Although in the drawing the non-slip of the present invention is illustrated as being circular in shape, it is to be understood that the present 20 invention is not limited to non-slips of that shape but in fact, the procedure of the present invention is such that non-slips of any desired shape may be obtained by varying the shape of the openings cut in the quarter lining.

From the foregoing description it is apparent that many modifications of the non-slip shown in the accompanying drawing and hereinbefore described will present themselves to those skilled in the art without departing from the spirit of 30 this invention. It is to be distinctly understood, therefore, that such modifications and the use of such individual features and sub-combinations of features as do not depart from the spirit of this invention are, although not specifically described herein, contemplated by and within the scope of 35 the appended claims.

Having thus described the invention, what is claimed is:

1. A shoe comprising in combination, a lining 40 having an opening therein, a piece of non-slip material extending through said opening so as to be exposed on the interior of the shoe, and a sponge rubber cushion of smaller size than the exposed portion of the non-slip material and arranged behind the exposed portion of said non-slip material.

2. A shoe comprising in combination, a lining having spaced openings therein in the region of the heel, a piece of material extending through 50 said openings and over the intervening substance on the interior of the shoe, said piece having a central portion of substantially the same width as said openings and end portions of greater width interlocked with said openings.

3. A shoe comprising in combination, a lining having an opening therein, a piece of non-slip material arranged beneath the lining bridging said opening and extending therebeyond, and a sponge rubber cushion disposed beneath said non-slip material in alignment with said opening, said cushion being smaller than the opening in the lining.

4. In a shoe the combination with a lining having a hole therein of a non-slip device extending through said hole, said non-slip device comprising a sponge rubber cushion having a cover thereon, said cushion being smaller than the hole in the lining, and means connecting said non-slip 65 device to the shoe.

ARTHUR J. BRAUER.
FREDERICK P. WAGNER.
